METHOD OF AND APPARATUS FOR
INDEXING DIALS

Ernest Penker, Flushing, N. Y., assignor to Etched
Products Corporation, Long Island City, N. Y.,
a corporation of New York

Application May 2, 1942, Serial No. 441,436

4 Claims. (Cl. 101—4)

This invention relates generally to the manufacture of index dials and the like, as used in indicating instruments and similar devices, and is more particularly directed to a method and means for forming indicia, as numerals, letters and other characters or symbols, upon stamped or drawn metal dials, under pressure, to effect a partial displacement of the dial material for the formation of the defining surfaces thereof, in a sub-surface relationship, to the face of the dial.

In producing index dials, such, for example, as are essential in the assembly of certain types of aircraft indicating instruments, the indicia, usually numerals, have been impressed or stamped on the dial surface by utilizing a conventional set-up of complementary male and female dies, the female die being entered in the dial, which is in the form of an annulus with an integral base flange, to coact with the male die, as the latter is pressed into the outer periphery or face of the dial, in accordance with standard practice. While certain numerals, letters or other symbols may be fairly clearly defined in producing the impressions by the use of the complementary male and female dies, those characters or symbols in which defining lines or surfaces intersect or merge into others of a different order or different relative disposition, are not cleanly and sharply delineated. For instance, the jointure or merger of a horizontal line or surface with a vertical or oblique one, as in the formation of the numeral "4" or the junction of intersecting lines, as the diagonal lines constituting the letter "x," instead of being sharply and angularly delineated, as is requisite to a uniformly clean-cut readily readable imprint, is obscured by a more or less irregular fillet or web-like connection between the lines. This lack of uniformly clear and sharp definition of all of the characters carried by the dial, it has been found, detrimentally affects the serviceability of the instrument in which the dial is designed to function, under variable and frequently abnormal conditions of use.

To overcome the unsatisfactory results which flow from the employment of the conventional male and female die methods and obtain the required uniformity and complete clarity of definition of all of the characters or symbols, it has been proposed to resort to engraving, or, as an alternative, to produce the indicia by an etching process. However, the use of either of these methods is objectionable, since it would not only appreciably retard production, but add materially to the cost of the dials and of the instruments of which they are to become a part.

Therefore, it is the primary object of this invention to provide a simple, efficient and economical method of producing characters, as numerals, letters or other symbols, upon stamped or drawn articles, as index dials, for indicating instruments and the like, which will insure uniformly clear and sharply delineated characters, irrespective of the relative arrangement or disposition of their component defining lines, the objectionable malformation of meeting and intersecting lines at their points of merger or jointure, which results from the use of the conventional male and female die stamping operations, as hereinbefore set forth, being entirely eliminated.

More specifically, it is an important object of this invention to provide a method of forming characters as aforesaid, on metal index dials, under pressure, to displace the dial material outwardly of the peripheral surface, from which the characters are to be viewed, as by coining, in a manner, whereby the displacement of material will be accurately controlled, directionally and otherwise, to produce a groove-outlined character in the dial surface, unmarred by irregularities in the groove-defining or immediately adjacent surfaces, especially at those points where grooves intersect or connect one with another, the major displacement of metal being removed by machining following the coining step.

It is also an important object of this invention to provide a simple and economical means or apparatus for practicing my method, whereby index dials may be rapidly and economically produced, with the elimination of those imperfections that are concomitant to the production of characters of the grooved-outline type, by standard male and female die processes, thus reducing the waste of material that results from the discarding of imperfect dials and greatly accelerating the aggregate output of dials over a given period.

A further object of my invention is to provide a mechanism for carrying my method into effect, as aforesaid, in which a series of characters, as numerals, letters or the like, may be simultaneously impressed on the circumferential face of a dial, in a coining action wherein the requisite impression-forming dies are concurrently urged into contact with the face of the dial and the impressions produced therein, in a continuing uniform movement thereof, under sustained and gradually increasing pressure.

Other objects and advantages flowing from the practicing of my invention will become manifest as the description proceeds, and I would have it

understood that my invention may be utilized in the application of grooved-outline characters to articles other than index dials of the form herein disclosed, within the spirit and scope of the appended claims.

In the accompanying drawings, I have shown a preferred form of mechanism for practicing my method, and a type of index dial which may be produced thereby, together with fragments of dial surfaces showing a numeral as produced by my method and by methods now employed, for comparative purposes.

In the drawings:

Figure 1 is a sectional elevation of a preferred embodiment of a coining or impression-forming mechanism, which may be advantageously employed in practicing my method.

Fig. 1a is a fragmentary enlarged sectional view, showing portions of the work-supporting element and cooperating pressure head in the position they assume at the beginning of the coining operation.

Figure 2 is a top plan view of a portion of the work-supporting element of the structure of Fig. 1, showing the relative disposition thereon of the concurrently actuatable dies and the cooperating work-retaining anvil.

Figure 3 is an exaggerated fragmentary view of an arcuate section of a dial, with a groove-forming portion of a die face entered therein, to disclose the manner in which the dial metal is displaced under the sustained and increasing die pressure.

Figure 4 is a view similar to Figure 3, showing the displaced excess metal removed from the face of the dial, following the completion of the coining operation.

Figure 5 is a view in perspective of an index dial in the form of an annulus, embodying an inturned attaching or mounting flange.

Figure 6 is an elevational view of a fragment of a dial, illustrating the clear definition of a numeral formed by my coining method, and

Figure 7 is a similar view, illustrative of the relative imperfections that would occur in the same numeral, as produced in the conventional stamping process.

Referring now to the drawings in detail, in which like characters of reference are employed to designate similar parts in the several views, 10 indicates the bed of an apparatus for practicing my method, embodying a rectangular recess 11 which may be formed by a suitable frame fixed to the bed surface, two of the members of which are indicated at 12 and 13. Projecting upwardly from the center of the aforesaid recess is a pin 14 having a head 15 countersunk in said bed and fixed thereto, as by the bolts 16, the end of said pin being slightly tapered or of a conical formation, as at 14a, for the purposes which will be explained.

A rectangular table 17 complementary to the recess 11 is supported in normally spaced relation to the bed 10 for relative vertical movement, by a plurality of expansion coil springs 18, the ends of which are engaged in the seats 19 and 20, formed in the opposed surfaces of the table and bed respectively, a spring being located in proximity to each corner of the table, so as to maintain it in a horizontal position. As will be noted, the table 17 is centrally bored, as at 10a, to provide a bearing for the aforesaid pin 14 which functions as a guide in the movement of the table in opposition to and under the influence of its supporting springs, relatively to said bed 10.

A work-retaining anvil, composed of two separate approximately semi-annular sections 21 and 21a, is located centrally of the table 17, the respective anvil sections being connected to the table by the screws 22 and 22a for relative horizontal movement within the limits defined by the cooperating elongated slots 23 and 23a formed in said anvil sections, as shown in Figure 2. The opposed surfaces of the two anvil sections are centrally recessed for the reception of the pin 14, the upper portions of the respective recesses being of reduced diameter, as at 24 and 24a, for engagement by the tapered portion 14a of said pin, in a camming action tending to separate said anvil sections, as the table is moved downwardly over the pin in opposition to the springs 18, for ultimate disposition upon the bed within the recess 11, preliminary to the performance of the coining operation, as will be hereinafter set forth in greater detail.

Radially disposed on the table 17, I provide a series of guideways 25 of a V or other suitable cross-section, in which complementary dependent tongues 26 of the dies 27 are adapted to be entered for movement of the dies longitudinally of the guideways, in opposition to and under the influence of the springs 28, located within the guideways, in engagement with suitable stops 29 therein and the tongues 26 of said dies. The guideways 25 terminate in spaced relation to the anvil, the springs being effective upon the dies to urge them to a normal position in which their vertical impression-forming faces 27a are likewise spaced from the anvil, as clearly shown in Figure 1. As will be evident, any number of dies desired, below the maximum number of guideways, may be employed in a coining operation, the tongues of the dies being readily inserted from the outer ends of the guideways to locate the dies in engagement with the guideway surfaces on which they bear, the mechanism herein shown being designed for the simultaneous production of twelve die-impressions. Of course, a mechanism may embody a greater or lesser number of guideways to accommodate the required dies.

Reciprocable within a suitable bearing 30 and normally disposed in vertically spaced relation to the table 17, is a pressure head 31 of an area 50 in excess of that of the bed recess 11, which is undercut or recessed, as at 32, the defining wall 32a of the recess being of a frustro-conical configuration, and having the terminal edge 32b to engage the inclined arcuate end surfaces 27b of the dies 27 in a camming action to urge the dies toward the anvil, as hereinafter described. The base of the recess 32 is annularly recessed, as at 33, for the reception of the work-engaging pressure disc 34 supported from the pins 35, reciprocable within the bearings 36 in said head. Springs 37 interposed between said disc and the head surface, act to expel the disc from said annular recess 33, which is provided with apertures 34a for the reception of the protruding heads of the anvil section retaining screws 22 and 22a.

A plurality of pins 38 having heads 39 reciprocable within the bores 40, normally are projected from the head 31 by the springs 41, these pins, four in number, being preferably positioned in alignment with the table supporting springs 18, the head in juxtaposition to the pins 38 being bored, as at 42, to receive the complementary guide pins 43 carried by the table 17, contiguous to the four corners thereof, as shown in Figure 2.

Assuming that a dial of the type shown in Figure 5 is to be imprinted or indexed, it is placed in position upon the sectional anvil with its flange *a* uppermost, the wall *b*, which is to form the face of the dial, being in the plane of the surrounding die faces. As the pressure head 31 is lowered toward the table 17, the guide pins 43 enter the head bores 42, the pins 38 contacting with the surface of the table in the continuing downward movement of the head and initiating a like directional movement of the table in opposition to its springs 18, as the latter yield under the resistance offered by the heavier springs 41. The continuing downward movement of the table, under pressure of the latter springs, upon the pin 14 brings the latter into the area of the recess formed in the opposed surfaces of the anvil sections and as the table is urged to its ultimate position in contact with the bed 10, the cam portion 14a of said pin enters the reduced diameter portion 24a of the anvil and initiates a gradual separating movement of the anvil sections for engagement with the inner surfaces of the dial wall *b*, the anvil sections reaching their extreme positions in positive frictional engagement with the dial, when the table comes to rest within the recess 11. This gradual actuation of the anvil sections and the progressive increase in the pressure that is applied to the dial wall flows from the cushioning action of the springs 18 in controlling the descent of the table and the concurrent projection of the pin 14 therethrough between the anvil sections. The possibility of distortion of the thin metal wall of the dial, as would result under the impact of an abrupt expansion of the anvil sections is thus entirely eliminated.

As the table 17 reaches its position within the recess 11, the continued approach of the pressure head causes the springs 41 to contract to permit the disc 34 to yieldably abut upon the flange *a* of the dial, under the control of the springs 37, the pressure imposed upon the dial by the disc increasing in the recession of the disc, concurrent with the engagement of the die ends 27b by the edge 32b of the wall 32a of the pressure head recess 32, as shown in Fig. 1a.

The continuing descent of the head with its edge 32b in engagement with the inclined surfaces 27b of the ends of the dies, simultaneously produces a uniform movement of the dies toward the dial to contact with the face thereof and transfer the characters delineated upon the die faces by wedge-like projecting surfaces to the dial in a continuing movement, in which the pressure, effective axially of the dies, is gradually increased as the edge 32b of the wall 32a traverses the inclined curved surfaces 27b of the dies, the die progression terminating in a final relatively abrupt pressure-applying movement, induced by the engagement of said edge 32b with the sharp terminal edge 27c of the inclined die surface, to complete the coining operation, the depth of the recessed portion 32 of the pressure head being just sufficient to permit of the engagement of the edge 32b with the edge 27c, as aforementioned.

As the dial is subjected to the progressively increasing pressure of the entering dies, the metal of the dial, within the area in which the wedge-like surfaces of the die faces are effective, is displaced in opposite directions, inwardly and outwardly, in response to and under the control of the die movement, the major displacement or shifting of the metal, indicated at *x* in Figure 3,

being outwardly of the dial face and laterally of the grooves produced therein, as controlled by the spreading and erupting action of the wedge-like formation of the die faces as they enter the metal in the formation of the grooves, whereby the characters are delineated on the dial. The expanded anvil, the periphery of which is complementary to the inner circumference of the dial, contributes to the limitation of the inward displacement of the dial metal, as at *y* in Figures 3 and 4, and a slight flattening or spreading thereof, as the metal is extruded in the coining action of the mechanism.

Following the completion of the coining operation, as just described, the pressure head may be raised, to permit the table to assume its normal position under the expanding action of the springs 18, whereupon the dial may be freely lifted from the anvil sections. The dial is then subjected to a milling or other suitable machine operation for effecting the removal of the displaced or surplus metal *x* from the face thereof. In this operation, only the outwardly displaced metal is removed, so that on the conclusion of the machining, the original outer circumferential dimension of the annulus will remain unchanged.

By utilizing a plurality of dies concurrently co-acting with the anvil, in the manner set forth, I am enabled to attain the heretofore described clean and sharp delineation in each character impressed in the dial metal, in a single continuing operation. Each constituent groove of a character is uniformly defined and the uniform displacement of the metal outwardly of the dial face, brought about by the co-action of the wedge-shaped die surfaces with the opposed dial supporting surfaces of the anvil, produces an even distribution of the metal between the character-defining grooves. This distribution of the surface metal, eliminates the malformation or bulging in the area of the juncture of one groove with another, as where one groove crosses another, or where two grooves meet, that is a common fault in the practicing of the conventional male and female die stamping processes, hereinbefore referred to, and which results in irregularities in the groove-defining lines and surfaces at such points, or in the formation of undesired connecting webs or fillet-like surfaces therebetween. Obviously, clear and sharp delineation of the characters in such circumstances, cannot be attained.

In Figure 6, I have illustrated the numeral "4" as it is produced on the face of a dial such as herein shown, by my method, while Figure 7 shows the same numeral as formed in a conventional male and female die operation. It will be observed that the numeral of Figure 6 is clear cut and sharply delineated, the point at which the horizontal portion of the numeral merges into or joins the vertical section thereof being defined by sharp angles, which produce a perfectly formed and symmetrical character, while the appearance of the numeral of Figure 7 is marred by the web-like or fillet connection between its horizontal and vertical portions, which interrupts the uniformity of the defining grooves.

From the foregoing, it will be manifest that I have provided a simple and highly practicable method of attaining the objectives of my invention, as hereinbefore set forth, together with a mechanism whereby my method may be practiced in a most efficient and economical manner.

I claim:

1. A mechanism for producing index dials and

the like, comprising a fixed base, an expandible work-engaging anvil, a vertically movable support for said anvil, a plurality of radially disposed guideways on said support, each being adapted to receive a die for movement longitudinally thereof, each of said dies being provided at one end thereof with an inclined surface having a sharp terminal edge, yieldable means for normally maintaining said support in vertically spaced relation to said base, a downwardly movable head mounted above the support, pins projecting from said head for engaging the support in the downward movement of the head and depressing the support into contact with said base, means rigid with said base for guiding the support in its movement toward the base and expanding said anvil to engage the work, said pins being yieldably mounted on the head to permit a continued downward movement of this latter subsequently to the depression of the support, and a surface formed on the head adapted to engage said inclined surfaces of the dies during the continued downward movement of the head to progressively urge said dies toward the anvil into impression forming engagement with the work thereon, said surface of the head engaging said sharp terminal edge of the inclined die surfaces at the end of the downward movement of the head to cause a final abrupt pressure applying movement of the dies.

2. A mechanism for producing index dials and the like, comprising a fixed base, an expandible work-engaging anvil, a vertically movable support for said anvil, a plurality of radially disposed guideways on said support, each being adapted to receive a die for movement longitudinally thereof, each of said dies being provided at one end thereof with a cam surface having a sharp terminal edge, yieldable means for normally maintaining said support in vertically spaced relation to said base, a downwardly movable head mounted above the support, pins projecting from said head for engaging the support in the downward movement of the head and depressing the support into contact with said base, means rigid with said base for guiding the support in its movement toward the base, said guide means being effective at a predetermined point in the movement of the support to expand said anvil to engage the work, said pins being yieldably mounted on the head to permit a continued downward movement of this latter subsequently to the depression of the support, and a surface formed on the head adapted to engage and traverse said cam surfaces of the dies during the continued downward movement of the head to progressively urge said dies toward the anvil to apply a gradually increasing impression forming pressure to the work thereon, said surface of the head engaging said sharp terminal edge of the inclined die surfaces at the end of the downward movement of the head to cause a final abrupt pressure applying movement of the dies.

3. A mechanism for producing index dials and the like, comprising a fixed base, an expandible work-engaging anvil, a vertically movable support for said anvil, a plurality of radially disposed guideways on said support, each being adapted to receive a die for movement longitudinally thereof, each of said dies being provided at one end thereof with an inclined surface having a sharp terminal edge, yieldable means for normally maintaining said support in vertically spaced relation to said base, a downwardly movable head mounted above the support, pins projecting from said head for engaging the support in the downward movement of the head and depressing the support into contact with said base, means rigid with said base for guiding the support in its movement toward the base and expanding said anvil to engage the work, said pins being yieldably mounted on the head to permit a continued downward movement of this latter subsequently to the depression of the support, means associated with the head and effective in the continued downward movement of this latter to yieldably press the work into engagement with the top of the anvil, and a surface formed on the head adapted to engage said inclined surfaces of the dies during the continued downward movement of the head to progressively urge said dies toward the anvil into impression forming engagement with the work thereon, said surface of the head engaging said sharp terminal edge of the inclined die surfaces at the end of the downward movement of the head to cause a final abrupt pressure applying movement of the dies.
4. A mechanism for producing index dials and the like, comprising a fixed base, an expandible work-engaging anvil, a vertically movable support for said anvil, a plurality of radially disposed guideways on said support, each being adapted to receive a die for movement longitudinally thereof, each of said dies being provided at one end thereof with an inclined surface having a sharp terminal edge, yieldable means for normally maintaining said support in vertically spaced relation to said base, a vertically movable head adapted to engage the support and depress the same into contact with said base, means rigid with said base for guiding the support in its movement toward the base and expanding said anvil to engage the work, and a surface formed on the head adapted to engage said inclined surfaces of the dies in a continued downward movement of the head subsequently to the depression of the support, to progressively urge said dies toward the anvil into impression forming engagement with the work thereon, said surface of the head engaging said sharp terminal edge of the inclined die surfaces at the end of the downward movement of the head to cause a final abrupt pressure applying movement of the dies.

ERNEST PENKER.
